CLAIM

The ornamental design for a mop head, as shown and described.

DESCRIPTION

FIG. 1 is a top plan view of the design of my present invention;

FIG. 2 is a front elevational view, the rear view being a mirror image;

FIG. 3 is a left end view;

FIG. 4 is a right end view;

FIG. 5 is a bottom plan view;

FIG. 6 is a perspective view of the design of my present invention as folded for use, illustrating a handle attachment which is shown in phantom;

FIG. 7 is a top view of the design of my present invention as folded for use;

FIG. 8 is a front elevational view of the design of my present invention as illustrated in FIG. 7, the rear view being a mirror image;

FIG. 9 is a left elevational view of the design of my present invention as illustrated in FIG. 7;

FIG. 10 is a right elevational view of the design of my present invention as illustrated in FIG. 7; and,

FIG. 11 is a bottom view of the design of my present invention as illustrated in FIG. 7.

The broken line showing of the handle attachment in FIG. 6 is for illustrative purposes only and forms no part of the claimed design.
